PUMP AND SHAFT HOUSING

John G. Wessels, Dallas, Tex., assignor, by mesne assignments, to Champion Cooler Corporation, Denison, Tex., a corporation of Texas

Filed Feb. 10, 1959, Ser. No. 54,547

Term of patent 14 years

(Cl. D65—1)

FIGURE 1 is a front elevation of a pump and shaft housing, embodying my new design;

FIGURE 2 is a top view of the same;

FIGURE 3 is a side view having a portion thereof in section; and,

FIGURE 4 is a view of the opposite side thereof.

I claim:

The ornamental design for a pump and shaft housing, substantially as shown.
